UNITED STATES PATENT OFFICE.

HUGH C. KELLEY, OF SONORA, TEXAS.

SHAMPOO-REGISTERING DEVICE.

No. 848,660.

Specification of Letters Patent.

Patented April 2, 1907.

Application filed December 21, 1906. Serial No. 348,945.

To all whom it may concern:

Be it known that I, HUGH C. KELLEY, a citizen of the United States, residing at Sonora, in the county of Sutton and State of Texas, have invented a new and useful 5 Shampoo-Registering Device, of which the following is a specification.

This invention relates to registering devices intended for use in barber-shops and 10 shampooing establishments to record each time the attendant uses the washing liquid, hair-tonic, and other liquids necessary for shampooing, so that the proprietor of the establishment will be enabled to keep an accurate and reliable record of the number of 15 persons the attendant or attendants treat.

The invention has for one of its objects to improve and simplify the construction and 20 operation of devices of this character, so as to be highly useful and efficient and comparatively inexpensive and simple to construct.

A further object of the invention is the provision of a supporting-shelf provided 25 with a number of registering devices and means associated with the shelf which causes the bottles as they are taken off or placed on the shelf to actuate the recording devices.

With these objects in view and others, as 30 will appear as the nature of the invention is better understood, the invention comprises the various novel features of construction and arrangement of parts, which will be 35 more fully described hereinafter and set forth with particularity in the claims appended hereto.

In the accompanying drawings, which illustrate one of the embodiments of the invention, Figure 1 is a front view of the bottle-support and registering devices thereon. 40 Fig. 2 is a side view. Fig. 3 is an enlarged detail view of one of the registering devices.

Corresponding parts in the several figures 45 are indicated throughout by similar characters of reference.

Referring to the drawings, 1 designates a suitable support, which may be in the form of a shelf to be attached to the wall or mirror 50 case of the barber-shop, and in the shelf portion 2 thereof are a plurality of openings in each of which is a vertically-movable follower 3 for supporting the various bottles 4.

Associated with each follower is a registering 55 mechanism (designated generally by 5) for

the purpose of registering the act of taking off a bottle or putting it back.

In order to insure the actuation of the registering mechanism, a spring-holder 6 is provided for each bottle, so as to engage 60 the neck portion thereof to insure the depression of the follower as the bottle is placed in position. The holder 6 is arranged on the shelf 1 a suitable distance above its companion follower and co-operates with the latter for incidentally preventing the bottle 65 from being accidentally knocked over.

In order to place a bottle in position after it has been used, the bottom of the bottle is first placed on its follower and then a downward pressure applied, so as to depress the follower sufficiently to permit the enlarged portion of the bottle to engage under the companion spring-holder 6. In thus depressing the follower the registering device is 75 caused to advance one point. From this it will be seen that the attendant must cause the device to register every time a bottle is taken off and returned, so that a complete record of all the operations can be readily and 80 conveniently kept.

The indicating devices 5 may be of any approved type and are preferably inclosed in a casing 7, so as to prevent tampering or unauthorized manipulation therewith. Each 85 device comprises a dial 8, having suitable divisions thereon, and a hand 9, which is connected with the toothed wheel 10 by the shaft 11. The wheel is actuated by the pawl 12, arranged in co-operative relation with the adjacent follower, and coacting with the pawl 12 is a hold-back-pawl 13, so that as the follower is moved up and down the hand 9 is advanced a point over the dial. The active 95 pawl 12 is mounted in a guide 14 and is provided with a spring 15 for raising it upwardly when the bottle is removed and the follower raised. A suitable means, such as a spring 16, is provided for causing the follower to move upwardly when the bottle is removed. 100

From the foregoing description, taken in connection with the accompanying drawings, the advantages of the construction and of the method of operation will be apparent to those skilled in the art to which the invention appertains, and while I have described the principle of operation of the invention, together with the device which I now consider to be the best embodiment thereof, I desire to have it understood that the device 105 110

shown is merely illustrative and that various changes may be made when desired as are within the scope of the claims.

What is claimed is—

- 5 1. In a device of the class described, the combination of a support, a movable member thereon for holding a bottle, a registering device actuated by the member, and means arranged on the support for compelling the member to be moved as the bottle is placed in position.
- 10 2. In a device of the class described, the combination of a support, a movable member theron, a registering device on the support arranged to be actuated by the said member, and a fixed bottle-holding device on the support arranged to cause the member to be moved by the bottle as the latter is engaged with the holding device.
- 15 3. In a device of the class described, the combination of a support having a plurality of openings, followers movably mounted in the openings, a registering device associated with each follower to be actuated thereby,

and a spring-holder on the support arranged above each follower for engaging the neck portion of the bottle and acting through the latter to hold the adjacent follower depressed.

4. In a device of the class described, the combination of a support having a plurality of openings, vertically-movable followers in the openings for receiving the bottles, a registering device located under each follower for actuation thereby, a casing for the registering devices, a plurality of spring-holders arranged in a position to require the followers to be depressed to place the bottles in position and adapted to engage the upper portions of the bottles to hold them in place.

In testimony that I claim the foregoing as my own I have hereto affixed my signature in the presence of two witnesses.

HUGH C. KELLEY.
